ABSTRACT

A gain control circuit in which a signal current source that has a constant average value and is modulated by the signal to be controlled is connected in the emitter circuit of a gain control transmitter the equivalent AC base-collector impedance of which is controlled by a control voltage applied to the base electrode. A controlled fraction of the signal current flows through a load impedance in series with the collector output circuit of the gain control transistor.

GAIN CONTROL CIRCUIT

BACKGROUND OF THE INVENTION

1. Field of the Invention

This invention relates to the field of gain control circuits and particularly to gain control circuits for high frequency signals and to delayed automatic gain control circuits in multi-stage amplifiers.

2. The Prior Art

Gain control circuits have been widely used in electronic circuits, and although there are many gain control circuit configurations, the desired characteristics have not been completely fulfilled. It is desirable that the circuit configuration be simple and that it be easy to select the correct values for the components and easy to determine the maximum attenuation possible with the chosen circuit. In addition, it is desirable that the input and output impedances and the direct voltage level at the output terminal remain constant when the gain of the circuit is varied.

Some of these characteristics are not compatible with each other. It has been difficult in the prior art to obtain, in a single circuit, many of these desired features, especially when the signal to be controlled had a high frequency. Another difficulty has been obtaining a gain control circuit to control a plurality of amplifiers at one time, as is frequently necessary when several stages are to be controlled by applying an automatic gain control (AGC) signal to them in parallel.

It is an object of the present invention to provide a gain control circuit that includes, simultaneously, a large number of the aforementioned desired characteristics.

Another object is to provide this improved gain control circuit in a configuration suitable for controlling high frequency signals.

A further object is to provide a gain control circuit that can be included in several stages, all of which can then be controlled by a single AGC signal source.

SUMMARY OF THE INVENTION

In accordance with the present invention, a gain control transistor has a signal current circuit connected to its emitter and in series with its emitter-base input circuit. The signal current circuit has a sufficiently high effective output impedance so that the quiescent current through it is substantially constant, although the actual, instantaneous value varies in accordance with the signal. The circuit is a grounded-base circuit so that the base of the control transistor is effectively grounded for signal frequencies although the biasing voltage, which may be obtained from an AVC rectifier circuit, is normally different from zero and is varied to control the base-collector impedance and, thus, the gain of the transistor. A load impedance is connected in series with the collector of the transistor so that a controlled amount of the signal current flows through the load impedance.

The constant current source is normally the emitter-collector circuit of a transistor that operates as a grounded-emitter circuit. The magnitude of current is controlled by a signal voltage applied to the suitably biased base-emitter input circuit.

The emitter of a third transistor may be connected to the collector of the gain control transistor, and the collector of the third transistor connected to the load impedance. This transistor is connected in a grounded

base amplifier circuit so that the output impedance of the overall circuit will be held constant, even when the bias on the gain control transistor is changed to change the gain of the circuit. The base of the third transistor

5 may be held at a suitable fixed bias level. Alternatively, it may be connected to the source that biases the base of the gain control amplifier, to control the sensitivity of the gain control circuit with reference to the variable direct voltage of the gain control signals.

10 The invention may also be embodied in a delayed AGC circuit for a multi-stage amplifier. In that embodiment a separate gain control circuit is included in each of the cascade-connected stages, but all of the control circuits are connected to a common AGC signal source.

15 AGC delay action is obtained by selecting the respective direct bias voltages to have different values at the collector electrodes of the gain controlled transistors.

BRIEF DESCRIPTION OF THE DRAWINGS

FIG. 1 is a schematic circuit diagram showing a basic gain control circuit according to the present invention.

FIG. 2 is an equivalent circuit of the circuit shown in FIG. 1.

25 FIG. 3 is a schematic circuit diagram of a practical embodiment of the gain control circuit of the present invention.

FIGS. 4-6 are circuit diagrams of different embodiments of the invention.

30 FIG. 7 is a graph illustrating the difference in operation between the circuits in FIGS. 5 and 6.

FIG. 8 is a schematic circuit diagram of a multi-stage amplifier incorporating the present invention.

35 DESCRIPTION OF THE PREFERRED EMBODIMENTS

In the fundamental circuit diagram shown in FIG. 1 a transistor Q_1 is connected in a grounded-base circuit. A signal current source 2 is connected between the emitter of the transistor Q_1 and ground, and the base of the transistor Q_1 is connected to ground through a voltage source V_C , which is the voltage that controls the gain of the transistor. The collector of the transistor is connected through a load impedance R_L to the power supply terminal 1. An output terminal 3 is connected to the common circuit point between the collector of the transistor Q_1 and the load impedance R_L .

40 The source 2 supplies a current that has a constant average value but varies about this average value in accordance with the signal to be controlled. Thus, it is convenient to refer to the source 2 as a constant signal current source, but with the understanding that this does not mean that the current has a fixed value.

45 The bias voltage source V_C as illustrated as being variable, and it is to be understood that this includes not only the possibility that the voltage may be a direct voltage capable of being set at different values within some predetermined range but may also be the output of an AGC circuit which varies at a relatively slow rate compared to the frequencies in the signal current from the source 2. Thus, the voltage V_C may be considered to be a direct voltage but not necessarily fixed at a single value.

50 60 65 The operation of the circuit in FIG. 1 will be explained in conjunction with the equivalent circuit shown in FIG. 2. The same reference numerals applicable to elements of FIG. 1 are also used in FIG. 2 to sim-

plify the explanation. In addition, in FIG. 2 the reference character Z_b designates an equivalent base impedance of the transistor Q_1 , the reference character Z_e designates an equivalent emitter impedance of the transistor Q_1 , and the reference character Z_{bc} is the equivalent impedance between the base and collector electrodes of the transistor. The current i_1 is the signal current from the source 2. The term α is the current amplification factor of the transistor Q_1 , and the current i_2 is the current through the load impedance R_L .

As indicated by the arrows, the net current flowing through the impedance Z_b is $i_1 - i_2$ and the signal voltage drop across Z_b , which is $(i_1 - i_2)Z_b$, is equal to the sum the voltage drop i_2R_L across the load impedance R_L due to the current i_2 plus the voltage drop $(i_2 - \alpha i_1)Z_{bc}$ across the impedance Z_{bc} due to the net current flow through the latter impedance. Combining all of these factors and separating out the currents i_1 and i_2 results in the following equation:

$$i_2 = Z_b + \alpha Z_{bc}/Z_b + Z_{bc} + R_L i_1$$

From equation (1) it can be seen that the ratio between the input and output signal currents i_1 and i_2 , which is the current gain of the circuit, is a function of Z_b , Z_{bc} , R_L , and α and can be controlled by controlling any of them. According to the present invention, the current gain of the circuit is controlled by controlling the equivalent impedance Z_{bc} between the base and collector electrodes of the transistor Q_1 , while the other factors Z_b , R_L , and α are maintained constant. The impedance Z_{bc} is controlled by changing the direct voltage V_C at the base electrode of the transistor Q_1 .

It is known that the impedance Z_{bc} can be controlled by the biasing voltage applied to the PN junction between the base and collector of the electrodes of the transistor Q_1 . The impedance value of Z_{bc} is very large when the PN junction is reversed-biased and becomes smaller and smaller as the PN junction is biased to the forward direction. It is also known that the impedance value of Z_{bc} varies with frequency so that there is a certain range of the control signal V_C when the impedance value of Z_{bc} becomes smaller for higher frequencies than for lower frequencies.

The present invention takes advantage of the frequency characteristic of the impedance Z_{bc} in order to provide a gain control circuit suitable for high frequency signals. When the voltage V_{bc} between the base and collector electrodes of the transistor Q_1 has the polarity and magnitude to reverse-bias the PN junction between the base and collector deeply, the impedance Z_{bc} reaches a high value in the order of several megohms for the signal frequency and is much larger than the impedance Z_b or the impedance of the load R_L . In that case, equation (1) may be simplified by neglecting the terms Z_b and R_L , leaving:

$$i_2 \approx \alpha Z_{bc}/Z_{bc} i_1 = \alpha i_1$$

When the direct voltage V_{bc} between the base and collector electrodes of the transistor Q_1 forward-biases the PN junction between these electrodes, the impedance Z_{bc} becomes smaller, and when the forward bias becomes large enough, the impedance Z_{bc} becomes negligible relative to the impedance Z_b and the load im-

pedance R_L . In that case, the factors involving the impedance Z_{bc} in equation (1) may be neglected, reducing equation (1) to the following approximate form:

$$i_2 \approx Z_b/Z_b + R_L i_1$$

3.

In equation (3) the impedance value of the load R_L is usually much larger than that of the equivalent base impedance of the transistor Q_1 , and equation (3) can therefore be simplified further to the following form:

$$i_2 \approx Z_b/R_L i_1$$

4.

It should be noted that equations (3) and (4) are satisfied only for higher frequencies and not for lower frequencies when the control voltage V_C has a relatively small value for forward biasing the PN junction between the base and collector electrodes. On the other hand, equations (3) and (4) are satisfied for both higher and lower frequencies when the control voltage strongly forward-biases the PN junction, because in that case the impedance Z_{bc} , which varies with frequency, is negligibly small.

According to one example of this invention, the range of the control voltage V_C is selected such that the impedance Z_{bc} is controlled only for signal frequencies and not for direct voltage or for the low frequencies that may be included in the control voltage V_C . Thus, the direct voltage of the output terminal 3 is maintained constant, while the current gain of the signals through the transistor Q_1 is controlled from the value α to the value Z_b/R_L , as shown in equations (1) and (4), respectively. The equivalent base impedance Z_b usually has a very small value relative to the load impedance R_L , as mentioned above, and so the current gain Z_b/R_L expressed by equation (4) is very small, much lower than unity. However, it is possible to increase impedance Z_b and the current gain by inserting an impedance, such as a resistor, in the base circuit of the transistor Q_1 . This simplifies the design of the circuit to obtain a given minimum gain or maximum attenuation of the signal.

FIG. 3 shows a practical circuit according to the present invention and uses the same components and reference characters as the circuits in FIGS. 1 and 2. The components so identified need not be described again. The current source 2 of FIGS. 1 and 2 has been replaced in FIG. 3 by a transistor Q_2 . This transistor may be referred to as the constant current transistor, and it is connected in a grounded emitter circuit. One terminal of a signal voltage source 4 is connected by way of a coupling capacitor C_1 to the base of the transistor Q_2 . The other terminal of the voltage source 4 is connected to ground. Two series-connected resistors R_1 and R_2 form a voltage divider across the power supply between the terminal 1, which has the voltage V_{CC} , and ground. The base of the transistor Q_2 is connected to the common circuit point between the resistors R_1 and R_2 , and the bias of the base-emitter circuit of the transistor Q_2 is determined by the voltage at this common circuit point in combination with the voltage across a resistor R_3 that connects the emitter of the transistor Q_2 to ground. A resistor R_4 is connected between the control voltage source V_C and the base of the gain control transistor Q_1 and may be referred to as a base resistor.

In the operation of the circuit in FIG. 3, a signal voltage applied to the base electrode of the transistor Q_2 from the signal voltage source 4 is converted to a signal current by the transistor Q_2 and is applied to the emitter electrode of the transistor Q_1 in accordance with the fact that the transistor Q_2 serves as the constant signal current signal transistor. The base resistor R_4 serves as one of the impedance elements that determine the maximum attenuation, or minimum gain, of the circuit according to equations (3) or (4).

The equivalent circuit of the schematic shown in FIG. 3 is almost the same as the equivalent circuit shown in FIG. 2, and it is therefore unnecessary to repeat the analysis of control operation.

The circuits shown in FIGS. 1 and 3 have a number of characteristics that are desirable in gain control circuits. In each instance, the circuit configuration is simple. Furthermore, the input impedance is maintained constant when the gain is being varied in accordance with the gain control operation. This is because the signal input transistor Q_2 is operated in its active region as a constant current source. In addition, the attenuation of the circuit is easily calculated by selecting the resistance values of the load impedance R_L and the base resistor R_4 . Another advantage is that the direct voltage level of the output terminal 3 can be maintained constant when the gain control operation is being performed in a selected range of the gain control signal voltage V_C .

Another practical embodiment of the invention is shown in the circuit in FIG. 4, which also uses a number of the same components as the previous circuits and identifies these components by the same reference characters. In FIG. 4 a tuned circuit 5, which is a parallel-tuned tank circuit, is used as the load impedance R_L instead of the resistor indicated in FIGS. 1 and 3. The load impedance 5 includes a capacitor C_2 and an inductor L_1 connected in parallel. A resistor R_5 is also connected in parallel with the capacitor C_2 and the inductor L_1 to control the Q factor of the tuned load impedance 5.

The load impedance is not connected directly to the collector of the gain control transistor Q_1 but instead is connected to the collector of an amplifier transistor Q_3 which is connected in a grounded base circuit. A resistor R_6 connects the collector of the gain control transistor Q_1 to the emitter of the amplifier transistor Q_3 . The output terminal 3 is connected to a common circuit point between the tuned load impedance 5 and the collector of the transistor Q_3 , and the bias voltage for this transistor is obtained by means of a voltage divider comprising two resistors R_7 and R_8 connected across the power supply voltage V_{CC} between the terminal 1 and ground. The base of the transistor Q_3 is connected to the common circuit point between these two resistors, and a capacitor C_3 is connected across the resistor R_8 to ground the base of the transistor Q_3 for signal frequencies.

Basically, the operation of the circuit in FIG. 4 is almost the same as the operation of the circuits in FIGS. 1 and 3. The additional factor is the grounded base transistor Q_3 . The reason that the grounded base transistor Q_3 is added between the transistor Q_1 and the tuned load impedance 5 is because the equivalent impedance seen from the load impedance 5 looking toward the transistor Q_1 can be maintained high and almost constant when the value of the gain control signal

V_C changes. Thus, the Q factor of the tuned load impedance 5 is not influenced but is maintained constant when the value of the gain control signal V_C changes. If the transistor Q_3 were not connected in the circuit, 5 the tuned load impedance 5 would be connected directly to the collector electrode of the gain control transistor Q_1 . In that case, the equivalent impedance seen from the tuned load impedance 5 looking toward the transistor Q_1 would be influenced or changed when 10 the value of the gain control signal V_C changed. This is because the equivalent impedance Z_{bc} between the base and collector electrodes of the transistor Q_1 is controlled, or changed, in accordance with the gain control signal V_C . Thus, the Q factor of the tuned load impedance 5 would be influenced or deteriorated by the gain control signal V_C .

It is possible to omit the resistor R_6 between the collector electrode of the gain control transistor Q_1 and the emitter electrode of the amplifier transistor Q_3 , but the purpose of this resistor is to eliminate or decrease noise signals generated by the transistor Q_3 , especially when the equivalent impedance Z_{bc} of the base and collector electrodes of the transistor Q_1 is caused to be small due to the gain control signal V_C . The resistor R_6 20 keeps the equivalent emitter impedance of the transistor Q_3 relatively high, regardless of the equivalent impedance Z_{bc} of the transistor Q_1 . As a result, the gain of the transistor Q_3 with respect to noise signals is made 25 small and consequently the replica of the noise signals in the collector circuit of the transistor Q_3 or in the tuned load impedance is small.

FIGS. 5 and 6 also include a number of circuit components similar to those in the circuit of FIG. 4. FIG. 35 5 includes, in addition to the components of FIG. 4, another amplifier system 6 controlled by the same control signal voltage V_C as the amplifier system comprising the transistors Q_1 - Q_3 in FIG. 4.

In FIG. 6, instead of a single resistor connected between the base of the transistor Q_3 and ground, there 40 are two series connected resistors R_9 and R_{10} . Another resistor R_{11} is connected between the base of the gain control transistor Q_1 and the common circuit point between the resistors R_9 and R_{10} .

In FIGS. 5 and 6 the reference character V_2 designates the base voltage of the transistor Q_1 , and the voltage characteristics of the collector-emitter voltage V_{CE} of the transistor Q_1 relative to the base voltage V_2 are shown in FIG. 7. The straight line 10, represents the relationship between the voltage V_{CE} and the voltage V_2 in FIG. 5 and the straight line 11 illustrates the relationship between the voltage V_{CE} and the voltage V_2 in FIG. 6.

In FIG. 5 the gain control signal V_C is applied to the 55 base of the gain control transistor Q_1 and the sensitivity S of the gain control operation is expressed as follows:

$$S = 2A/2V_2 = 2A/2V_{CE} \cdot 2V_{CE}/2V_2$$

where:

A is the gain of the circuit;

V_2 is the base voltage of transistor Q_1 , and

V_{CE} is the collector-emitter voltage of transistor Q_1 .

In equation (5) $2A/2V_{CE}$ has a constant value determined by the transistor Q_1 so that equation (5) becomes:

$$S = K \cdot 2V_{CE}/2V_2$$

6.

where:

K is a constant and is equal to $2A/2V_{CE}$

From equation (6) it is to be understood that the sensitivity of the gain control operation of the circuit, which is expressed by the ratio of the increment of A to the increment of V_{CE} is determined by the ratio of the increment of V_{CE} to the increment of V_2 , where the base voltage V_2 is equal to the gain control voltage V_{CE} .

In the circuit of FIG. 5, the direct voltage at the collector electrode of the gain control transistor Q_1 , which is the reference voltage, is maintained constant relative to the base voltage when the direct voltage at the base electrode varied. Thus, the voltage characteristic of the voltage V_{CE} between the collector and emitter electrodes of the gain control transistor Q_1 relative to the base voltage V_2 of the same transistor can be drawn as a straight line 10 in FIG. 7 because the direct voltage at the emitter electrode changes linearly with respect to the direct voltage at the base of the electrode when the direct voltage at the collector electrode is maintained constant.

The sensitivity S of the gain control operation of the circuit in FIG. 5, which is determined according to equation (6), becomes relatively high compared to the sensitivity of the gain control operation of FIG. 6. When the sensitivity S of the gain control operation is high, the range of the control signal voltage V_C should be restricted to a limited set of values to obtain a desirable range of the gain of the circuit. Such a restriction of the range of the control voltage is often undesirable, especially when the gain of another amplifier system 6 is to be controlled by the same signal V_C in a different range of gain, such as occurs when a delayed AGC operation is performed.

The sensitivity S of the gain control operation of the circuit in FIG. 6 is reduced to make it less necessary to restrict control signal V_C . In FIG. 6 the resistors R_7 , R_9 , and R_{10} form a voltage divider across the power supply voltage V_{CC} between the terminal 1 and ground. The resistors R_9 and R_{10} are essentially substituted for the resistor R_8 in the circuit in FIG. 5, and the common circuit point between the resistors R_9 and R_{10} is connected to the control voltage V_C by way of a resistor R_{11} . Thus, a fraction of the control voltage V_C is connected to the base of the transistor Q_3 .

In analyzing the operation of the circuit of FIG. 6, it may first be supposed that the gain control voltage V_C is removed and that the base currents of the transistors Q_1 and Q_3 may be neglected. The following equations are then true:

$$V_1 = R_9 + R_{10} / R_7 + R_9 + R_{10} V_{CC}$$

55

7.

$$V_2 = R_{10}/R_7 + R_9 + R_{10} V_{CC}$$

8.

where V_1 and V_2 are the direct voltages at the base electrodes of the transistors Q_3 and Q_1 , respectively, when the control voltage V_C is removed.

In calculating the values of the circuit components in FIG. 6, the base voltages V_1 and V_2 of the transistors

Q_3 and Q_1 (when the control voltage V_C is removed) are first selected such that the gain of the circuit is a maximum and the resistance values of the resistors R_7 , R_9 and R_{10} are determined according to equations (7) and (8).

The value of the gain control signal voltage V_C is selected to be larger than the base voltage V_2 expressed by equation (8) and applied not only to the base of the transistor Q_1 but also to the base of the transistor Q_3 . Therefore, when the gain control voltage, V_C is applied, the base voltage of the transistor Q_1 is increased compared with the voltage V_2 and expressed by the equation (8). The base voltage of the transistor Q_3 is also increased compared with the voltage V_1 and expressed by equation (7). As a result, the collector voltage of the transistor Q_1 , which is the reference voltage relative to the base voltage of the same transistor is also increased. Accordingly, the sensitivity S of the gain control operation of the circuit is reduced as compared with that of the circuit in FIG. 5 because the collector voltage of the transistor Q_1 is changed by the gain control voltage V_C in the same direction as that of the base voltage of the same transistor.

The operation of the circuit in FIG. 6 when the gain control voltage V_C is applied is made more clear by following equations. When the gain control signal V_C is applied, and the base currents of the transistors Q_1 and Q_3 are neglected, the following equations hold true:

$$V_2 = i_3 R_{10} + i_4 (R_{10} + R_{11}) \quad (9).$$

$$V_1 = V_{CC} - i_3 R_7 \quad (10).$$

$$V_{CC} = i_3 (R_7 + R_9 + R_{10}) + i_4 R_{10} \quad (11).$$

where:

V_2 and V_1 are the direct voltages at the base electrodes of the transistors Q_1 and Q_3 , respectively;

i_3 is a current which flows through the resistors R_7 and R_9 ; and

i_4 is the current that flows through the resistor R_{11} . The current i_3 may be determined from equations (9) and (11) to be:

$$i_3 = V_{CC}(R_{10} + R_{11}) - V_2 R_{10} / (R_7 + R_9) R_{10} + (R_7 + R_9 + R_{10}) R_{11} \quad (12).$$

If the voltage V_{be} between the base and the emitter electrodes of the transistor Q_1 equals that of the transistor Q_3 and the voltage drop V_d across the resistor R_6 is maintained constant, the voltage V_{CE} between the collector and emitter electrodes of the transistor Q_1 is expressed as follows:

$$V_{CE} = V_1 - V_2 - V_d \quad (13).$$

Substituting equations (10) in equation (13) yields

$$V_{CE} = (V_{CC} - i_3 R_7) - V_2 - V_d \quad (14).$$

Substituting equations (12) in equation (14) yields

$$V_{CE} = V_{CC} - V_{CC}(R_{10} + R_{11}) - V_2 R_{10} / (R_7 + R_9) R_{10} + (R_7 + R_9 + R_{10}) R_{11} \cdot R_7 - V_2 - V_d \quad 15.$$

The ratio between the increments of the voltage V_{CE} of the transistor Q_1 and the gain control signal voltage V_C , which is equal to the base voltage V_2 of the same transistor, is found by differentiating V_{CE} with respect to V_2 in equation (15) as follows:

$$2V_{CE}/2V_2 = 2V_{CE}/2V_2 = R_{10} R_7 / (R_7 + R_9) R_{10} + (R_7 + R_9 + R_{10}) R_{11} - 1 \quad 16.$$

In equation (16), when the resistance R_{11} is infinite, the equation reduced to:

$$2V_{CE}/2V_2 = -1 \quad 17.$$

The resistor R_{11} is not used in the circuit in FIG. 5 and so the equation (17) is satisfied by that circuit. Thus, the sensitivity S of the gain control operation in FIG. 5 is high.

However, the resistance value of the resistor R_{11} is finite in the circuit in FIG. 6 and so equation (17) is not satisfied. As a result, the relationship between the voltages V_{CE} and V_2 corresponds to the straight line 11 in FIG. 7, and the change of the voltage V_{CE} relative to a change of the voltage V_2 is smaller than in the circuit of FIG. 5. Thus, the sensitivity S of the gain control operation of FIG. 6 is reduced relative to that in FIG. 5.

The resistance values R_7 , R_9 , R_{10} , and R_{11} may be selected to satisfy the following equation as an example:

$$R_{10} R_7 / (R_7 + R_9) R_{10} + (R_7 + R_9 + R_{10}) R_{11} = \frac{1}{2} \quad 18.$$

Substituting (18) in equation (16) yields:

$$2V_{CE}/2V_2 = -\frac{1}{2} \quad 19.$$

From equations (6), and (18) and (19) it can be seen that the sensitivity of the gain control operation of the circuit in FIG. 6 is half the value of that of FIG. 5 when the resistance values R_7 , R_9 , R_{10} , and R_{11} are selected to satisfy equation (18).

When the sensitivity S of the gain control operation is chosen, the range of the control signal voltage V_C can be increased to permit the gain of another amplifier system 6 to be controlled in a different range of gain, such as may be required for a delayed AGC operation.

FIG. 8 shows a circuit similar to that in FIG. 6 but with a second set of components to form a multi-stage amplifier. In FIG. 8, the signal voltage source 4 supplies high frequency signals, such as intermediate frequency (i.f.) signals of a television receiver, to the base electrode of the transistor Q_2 . The circuit configuration includes a pair of gain controlled amplifiers 12 and 13 connected in cascade, each of which is fundamentally similar to the circuit in FIG. 4.

The first amplifier 12 consists of the transistors Q_1 , Q_2 , and Q_3 , and a tuned load impedance, or tank cir-

cuit, 5. The other gain control amplifier 13 includes the transistors Q_1' , Q_2' , and Q_3' , and a tank circuit 5'. The output terminal 3 of the first amplifier 12 is connected through a coupling capacitor C_4 to an input terminal 14 of the amplifier 13. A voltage divider comprising resistors R_7 , R_{12} , and R_{13} is connected between the power supply terminal 1 and ground. A common circuit point between the resistors R_7 , R_{12} is connected to the base electrode of the transistor Q_3 in the amplifier 12 and a 10 different common circuit point between the resistors R_{12} and R_{13} is connected to the base of the transistor Q_3' in the amplifier 13.

An AGC circuit 20 is connected to the bases of the two gain control transistors Q_1 and Q_1' in the amplifiers 12 and 13, respectively. Gain controlled output signals are obtained through the output terminal 3' of the amplifier 13 and are applied to an emitter follower transistor Q_4 . This transistor has an emitter-load R_{14} and is connected to an output terminal 15, which is the output 20 terminal for the entire circuit.

A point to be specifically noted in the circuit of FIG. 8 is that the voltages at the collector electrodes of the gain controlled transistors Q_1 and Q_1' , each of which is the reference voltage relative to the gain control signals supplied to the base electrode thereof, are different from each other. A delayed AGC operation is carried out in this way even though the AGC signals from the circuit 20 are applied in common to the base electrodes of both of the gain control transistors Q_1 and Q_1' . This 30 delayed AGC operation will now be explained in detail.

Due to the fact that the base electrodes of the transistors Q_3 and Q_3' are connected to different points along the voltage divider formed by the resistors R_7 , R_{12} , and R_{13} , the direct voltages at the base electrodes of the 35 transistors Q_1 and Q_1' are made different from each other. If the direct voltage V_{be} between the base and emitter electrodes of the transistor Q_3 is equal to that of the transistor Q_3' and if the direct voltage drop across the resistor R_6 is equal to that across the resistor R_6' , the direct voltage of the collector electrode of the 40 transistor Q_3 is different from and higher than that at the collector electrode of the transistor Q_3' by the amount of the direct voltage drop across the resistor R_{12} .

Each of the direct voltages at the collectors of the transistors Q_1 and Q_1' is a reference voltage relative to the respective gain control signals supplied to the base electrode of these transistors, so that the following 45 characteristics are obtained in the circuit:

1. When the gain control signal from the circuit 20 is in a relatively low range or level, only the amplifier 13 has its gain controlled and the amplifier 12 does not. This is because the collector voltage of the transistor Q_1' is selected to be lower than that of the transistor Q_1 , and only the voltage between the base and collector electrodes of the transistor Q_1' is in a range to control the equivalent impedance Z_{bc} thereof, as described previously in connection with FIG. 2. The voltage between the base and collector electrodes of the transistor Q_1 is not in a range to control the equivalent impedance Z_{bc} of that transistor.

2. When the gain control signal from the circuit 20 is in a higher range, or level, both of the amplifiers 12 and 13 have their gains controlled, because the voltage 60 between the base collector electrodes of the respective transistors Q_1 and Q_1' is in a range to control equivalent impedance Z_{bc} of the respective transistors.

3. When the gain control signal from the circuit 20 is still higher, only the amplifier 12 has its gain controlled, because in this range of the gain control signal, the voltage between the base and collector electrodes of the transistor Q_1' has reached a value such that the maximum attenuation, or minimum gain, of the amplifier 13 has been attained, according to equation (4) as discussed in connection with FIG. 2.

4. When the gain control signal from the circuit 20 is in a still higher range, neither of the amplifiers 12 and 13 has its gain controlled, because in this range of the gain control signal, the voltages between the base and collector electrodes of the transistors Q_1 and Q_1' are such that the maximum attenuation, or minimum gain, of the amplifiers has been reached according to equation (4).

It is to be understood from the preceding characteristic (1)-(4) that a delayed AGC operation is performed in the circuit of FIG. 8 where the AGC operation for the amplifier 12 of the preceding stage is delayed relative to that for the amplifier 13 of the succeeding stage. It may also be seen that the circuit configuration necessary to obtain the delayed AGC operation is very simple, because only the voltage dividing resistors R_7 , R_{12} , and R_{13} are used, and the AGC signals from the circuit 20 can be applied in common to the bases of the transistors Q_1 and Q_1' .

What is claimed is:

1. A gain control circuit comprising:

- A. a constant signal current source transistor having a base-emitter input circuit and an emitter-collector output circuit, said constant signal current source transistor being biased to operate in its active region; and being supplied with a signal voltage;
- B. a gain control transistor having base emitter, and collector electrodes;
- C. circuit means to connect said constant current source transistor output circuit in series with said gain control transistor emitter electrode;
- D. a load impedance connected to said gain control transistor collector electrode; and
- E. a gain control voltage source connected to said gain control transistor base electrode for forward-biasing the base-collector junction of said gain control transistor to control the base-collector impedance thereof so as to control the gain of said gain control transistor.

2. The gain control circuit of claim 1 comprising, in addition:

A. an amplifier transistor comprising:

- 1. an emitter and a collector connected in series between said collector of said gain control transistor and said load impedance, and
- 2. a base electrode; and
- B. means to bias said base electrode of said amplifier transistor.

3. The gain control circuit of claim 2 comprising a second impedance connected in series between said emitter of said amplifier transistor and said collector of said gain control transistor.

4. The gain control circuit of claim 3 in which said second impedance is a resistor.

5. The gain control circuit of claim 3 in which said load impedance is a parallel-tuned circuit responsive to said signal current.

6. The gain control circuit of claim 2 comprising, in addition:

- A. a second constant current transistor having a base-emitter input circuit and an emitter-collector output circuit;
- B. a second gain control transistor comprising:
  - 1. an emitter connected to said emitter-collector output circuit of said second constant current transistor,
  - 2. a base electrode, and
  - 3. a collector electrode;
- C. a second load impedance;
- D. a second amplifier transistor comprising:
  - 1. an emitter and a collector connected in series between said collector of said second gain control transistor and said second load impedance, and
  - 2. a base electrode;
- E. second biasing means to bias said base electrode of said second amplifier transistor; and
- F. a signal-transmitting connection from said first-named load impedance to said input circuit of said second constant current transistor.

7. The gain control circuit of claim 6 in which said second bias means biases said second amplifier transistor at a different bias voltage than the bias voltage applied to said first-named amplifier transistor by said means to bias the base electrode of said first-named amplifier.

8. The gain control circuit of claim 7 in which the bias voltage of said first-named amplifier transistor is closer to the collector voltage thereof than the bias voltage of said second amplifier is to the collector thereof.

9. A gain control circuit comprising:
a constant current transistor having a base-emitter input circuit and an emitter-collector output circuit;

means to connect said input circuit to a source of signal voltage;
a gain control transistor having base emitter, and collector electrodes;
circuit means to connect said constant current transistor output circuit in series with said gain control transistor emitter electrode;
a load impedance connected to said gain control transistor collector electrode;
a gain control voltage source connected to said gain control transistor base electrode to control the base-collector impedance of said gain control transistor to control the gain of said gain control transistor;

an amplifier transistor comprising:

- 1. an emitter and a collector connected in series between said collector of said gain control transistor and said load impedance, and
- 2. a base electrode; a second impedance connected in series between said emitter of said amplifier transistor and said collector of said gain control transistor;

means to bias said base electrode of said amplifier transistor; and
means to connect said gain control voltage source to said base of said amplifier transistor.

10. A gain control circuit comprising:

- A. an amplifier comprising first and second input terminals;

- B. gain control means connected to said first terminal to supply a variable control voltage thereto;
  - C. reference voltage means connected to said second terminal to supply a reference voltage thereto;
  - D. means in said amplifier to control the gain of said amplifier in accordance with the voltage difference between the control voltage supplied to said first terminal and the reference voltage supplied to said second terminal; and
  - E. means to connect said gain control means to said reference voltage means for adding a part of said variable control voltage to said reference voltage to reduce the sensitivity in the gain control operation of said amplifier.
11. A gain control circuit comprising:
- A. first and second amplifiers connected in series and each comprising:
    - 1. gain control means,
    - 2. a gain control terminal, and
    - 3. a reference voltage terminal;
  - B. gain control voltage supply means connected in

- common to both of said gain control terminals to supply the same gain control thereto;
- C. a voltage divider circuit coupled to a voltage supply source to derive therefrom first and second different reference voltages, said voltage divider circuit being connected to said reference voltage terminal of said first amplifier to supply said first reference voltage thereto; and
- said voltage divider circuit being connected to said reference voltage terminal of said second amplifier to supply said second reference voltage thereto, the gain of said first and second amplifiers being controlled, respectively, by the voltage difference between said variable control voltage applied to both of said gain control terminals and the respective reference voltage applied to the respective reference voltage terminal, whereby a delay action of the gain control operation is performed between said first and second amplifiers.
